UNITED STATES PATENT OFFICE.

OTTO WIGGERS, OF HOOPER, UTAH.

BURGLAR-ALARM.

1,078,476.

Specification of Letters Patent. Patented Nov. 11, 1913.

Application filed March 8, 1913. Serial No. 752,982.

To all whom it may concern:

Be it known that I, OTTO WIGGERS, a citizen of the United States, residing at Hooper, in the county of Weber and State of Utah, 5 have invented certain new and useful Improvements in Burglar-Alarms, of which the following is a specification, reference being had therein to the accompanying drawing.

This invention relates to a circuit closing 10 device which is used in combination with a safe and has for its special object the production of a device which will automatically close the circuit for ringing a bell, or for giving other notice when unauthorized access is 15 had to the interior of the safe.

Another object of this invention is the 20 production of a circuit closing device which will automatically close the circuit when the boxes contained within the safe are moved so as to allow the contact members to come into engagement.

With these and other objects in view, it 25 will be seen that this device consists of certain novel combinations, constructions and arrangement of parts as will be hereinafter fully described and claimed.

In the accompanying drawing: Figure 1 30 is a rear elevation of the safe showing the device attached thereto. Fig. 2 is a side elevation of the device showing the lower portion of the safe in vertical section. Fig. 3 is a perspective view of the circuit closing member. Fig. 4 is a top plan view of the device showing a portion of the safe in section; 35 Fig. 5 is a side elevation of a contact post and attaching means attached to a portion of the safe.

Referring to the accompanying drawing by numerals 1 indicates the safe which is 40 provided with a transversely extending opening 2 formed in its rear portion. This safe 1 may, of course, be of any construction such as the kind used in banks or upon a railroad car. The interior of this safe is 45 provided with the usual boxes 3 in which the money or other valuables are placed.

The rear portion of the safe 1 supports the insulated blocks 4 which carry the contact plates 5 which are supported thereon in 50 any suitable manner. These contact plates 5 carry the contact posts 6 to which the wires

7 are attached by means of the screw 8. The circuit closing member comprises an elongated spring member 9 which is attached to the body of the safe by means of the screws 55 10 passing through the apertures 11. The upper portion of this spring carries the plunger member 12 which is formed of insulated material such as rubber and through which the transverse contact bar 13 passes. 60 This plunger member 12 is slidably mounted within the opening 2 and normally bears upon one of the boxes 3. When this device is in position the bar 13 will be positioned so as to bear upon the contact plate 5 when the 65 plunger 13 extends into the safe whereby the circuit will be closed for ringing the bell.

In operation the boxes 3 are positioned within the safe whereby the plunger will be forced outwardly for disengaging the bar 13 70 from engagement with the plates 5. The current is then turned on. If unauthorized access is had into the interior of the safe, the boxes will, of course, be withdrawn whereby the spring 9 will force the plunger 12 into 75 the safe and will cause the bar 13 to come into engagement with the plates 5 for closing the circuit for ringing a bell or for giving other notice of the access to the safe.

It is, of course, obvious that this device 80 may be used in a safe such as used in banks for turning in an alarm at police headquarters or for use in a safe that is used in express cars for turning in an alarm into some other car upon the train. Any suitable 85 means, such as storage batteries, may be used for operating this device as the same will form a minimum current to operate the same.

Having thus described the invention, what 90 is claimed as new, is:—

In a device of the kind described in combination with a safe provided with a transverse opening and provided with an article upon its inner portion, a plurality of insulated members supported adjacent said opening, contact plates mounted upon said insulated members and provided with contact posts, a spring carried by said safe, a laterally extending plunger carried by said 100 spring and slidably mounted within said opening, a transversely extending contact

bar carried by said plunger, said spring normally exerting inward pressure upon said plunger, said contact bar adapted to engage said contact plates for closing the circuit for giving an alarm when the article contained in the safe is removed from the inner end of said plunger.

In testimony whereof I hereunto affix my signature in presence of two witnesses.

OTTO WIGGERS.
